UNITED STATES PATENT OFFICE.

BRADFORD L. WILLIAMS, OF CAMDEN, NEW JERSEY.

DESIGN FOR A HAND-OPERATED MASSAGE DEVICE.

46,240.

Specification for Design.

Patented Aug. 4, 1914.

Application filed May 12, 1914. Serial No. 838,158. Term of patent 3½ years.

To all whom it may concern:

Be it known that I, BRADFORD L. WILLIAMS, a citizen of the United States, residing at the city of Camden, in the county of Camden and State of New Jersey, have invented a certain new, original, and ornamental Design for a Hand-Operated Massage Device, of which the following is a specification, reference being had to the accompanying drawings, forming part hereof, in which—

Figure 1, is a top-plan view of the hand operated massage device of my new design; and Fig. 2, is a side elevational view of the said design, more particularly showing the ornamental cylindriform block within which

the series of concentric rings of independent rubber needles are arranged, the outermost ring of the rows of said needles off-set in respect to the upper edge of the block and flaring slightly to the middle of the block where is provided a circular recess in adjoining relationship to a rounded bead and therefrom merging into a flat surface extending to the base of said block.

I claim:

The ornamental design for a hand operated massage device, as shown and described.

BRADFORD L. WILLIAMS.
